UNITED STATES PATENT OFFICE.

PETER W. LAMBERT, OF HOBOKEN, NEW JERSEY.

DESIGN FOR A BELT-BAQ.

SPECIFICATION forming part of Design No. 12,206, dated March 29, 1881.

Application filed January 26, 1881. Term of patent 7 years.

To all whom it may concern:

Be it known that I, PETER WILLIAM LAMBERT, a citizen of the United States, residing at Hoboken, in the county of Hudson and State of New Jersey, have invented and produced a new and original Design for Belt-Bags, of which the following is a specification.

The design relates to belt-bags with rectilinear inclined sides, a rectilinear base, and broken edges; also, to a belt-bag having rectilinear sides, a rectilinear base, broken edges, and a series of terraces; also, to a belt-bag having two spherical projections at its upper end.

15 The drawing represents a front view of my belt-bag.

In this drawing, the letter A designates the body of my belt-bag, which is made with rectilinear inclined sides *a a*, a rectilinear base, *b*, and broken corners *c c*, whereby a novel and distinguishing appearance is imparted to it. Furthermore, my belt-bag is formed with terraces

d e f, and on its sides, near its top, are formed spherical projections *g g*.

What I claim as new, and desire to secure 25 by Letters Patent, is—

1. The within-described design for a belt-bag, consisting of the body A, having the rectilinear base *b*, the rectilinear inclined sides *a a*, broken corners *c c*, and terraces *d*, *e*, and *f*, all as shown and set forth.

2. The within-described design for a belt-bag, consisting of the body A, having the rectilinear base *b*, the rectilinear inclined sides *a a*, broken corners *c c*, terraces *d*, *e*, and *f*, 35 and spherical projections *g g*, all as shown and set forth.

In testimony whereof I have hereunto set my hand and seal in the presence of two subscribing witnesses.

PETER WILLIAM LAMBERT. [L. S.]
